UNITED STATES PATENT OFFICE.

FAY McDONALD, OF CINCINNATI, OHIO.

CORSET BRASSIÈRE.

Application filed June 8, 1925. Serial No. 35,536.

My invention relates to corset brassières in general and particularly to corset brassières adapted to support and reduce the abdomen and diaphragm.

5 It is the object of my invention to provide in a corset brassière, which will support the bust and the waist of the figure, an abdominal diaphragm supporting member which shall be adjustable in combination with the 10 corset brassière so that the two elements together will be adapted to hold in the abdomen and diaphragm.

The effect on the average woman's figure of dispensing with the support of stiff cor- 15 set stays has been to cause the abdomen and diaphragm to extend with a corresponding enlargement of the hips and it is therefore the object of my invention to provide a corset brassière which shall be adapted to 20 restrain the figure to the desired trim appearance, thereby correcting the improper developments of the diaphragm and abdomen caused by the wearing of insufficient or no corsets.

25 Referring to the drawing in which I have illustrated a preferred construction of a combined corset brassière and abdominal and diaphragm supporting piece:

The figure is a plan view of the corset 30 brassière laid open on a flat surface and viewed from the inner side of the garment.

The corset brassière generally indicated at 1 may be provided with suitable ribbed portions of bane, wires or the like stitched 35 within seams in the garment as indicated at 2. Further elastic segments 3 may be provided at various positions to hold the corset flat against the figure so that the outline of the corset will not show through the outer

40 clothing. The corset may be further provided with garter straps 4 for supporting the stockings on both sides of the legs. Hooks 5 may further be sewed onto one of the open ends of the garment which are 45 adapted to engage eyes 6 on the other open end and secure the garment about the body in the usual manner. The construction of the corset brassière and the disposition of the reinforcing strips, elastic segments and 50 hooks and eyes may be varied according to the style of figure for which the garment is provided and form no part of my invention.

In the figure the portion of the corset brassière adapted to fit over the hips in back 55 is indicated by the letter A. A reinforcing strip 7 with a loop 8 slidably retains an

adjustable belt 9. With the tightening of the belt a corresponding pull is exerted on the reinforcing strip 7 which tends to hold in the hips. The reinforcing strip in this 60 position serves a further purpose of preventing the tendency of outer garments being creased at this portion of the hips in back. An abdominal and diaphragm band piece 10 with one side extended as in the belt 9, is 65 secured to the portion of the garment adapted to cover the abdomen and dia- phragm in front. A buckle 11 secured to the side of the piece 10 opposite the strap may be used to draw the piece 10 securely 70 about the abdomen and diaphragm prior to the adjustment of the corset brassière. The abdominal band piece may be made from a single piece of material, or it may be made from segments with reinforced stays as in- 75 dicated. I have further found it preferable to sew the abdominal band in position with stitching as shown at 12.

In adjusting the garment the strap is ad- 80 justed and the abdominal supporting band is drawn tight across the abdomen and dia- phragm, and at the same time the hips are pulled in. After this operation the garment is secured with the hooks 5 and the eyes 6 in the usual manner. For appearance sake 85 it is preferable to have the supporting band on the inner side of the corset brassière, but modifications in structure will readily occur to those skilled in the art, such as reversing the band to the outer side of the garment, 90 without departing from the principle of my invention hereinbefore described.

Having thus described my invention, what I claim as new and desire to secure by Let- 95 ters Patent is:—

1. A body confining garment comprising a member to reach from above the busts to the lower portion of the abdomen, said body portion having elastic portions, giving elastic confinement to the abdominal re- 100 gions, means for reinforcing the portion of the garment above the abdomen and below the busts, across the front of the body, and means concealed beneath the garment when in use for adjusting the tension of the re- 105inforced front portion of the garment across the diaphragm independent of the elastic portion of the garment, in such a way as to hold the garment smoothly against the body across the diaphragm, said reinforcing 110 means formed as a non-elastic pad secured to the front of the garment and extending

across the diaphragm portion thereof, and having a member passing around the body beneath the garment when in use and secured adjustably to the pad again, thus serving as the adjusting means above referred to.

2. A body confining garment comprising a member to reach from above the busts to the lower portion of the abdomen, said body portion having elastic portions, giving elastic confinement to the abdominal regions, means for reinforcing the portion of the garment above the abdomen and below the busts, across the front of the body, and means concealed beneath the garment when in use for adjusting the tension of the re-

inforced front portion of the garment across the diaphragm independent of the elastic portion of the garment, in such a way as to hold the garment smoothly against the body across the diaphragm, said reinforcing means formed as a pad having approximately vertically disposed reinforcing ribs therein, said pad secured to the front of the garment and extending across the diaphragm portion thereof, and having a member passing around the body beneath the garment when in use and secured adjustably to the pad again thus serving as the adjusting means referred to.

FAY McDONALD.
